RADIO TIME SWITCH AND AUTOMATIC
TUNERCesare Mongelli and Charles Mongelli,
Brooklyn, N. Y.

Application March 10, 1932, Serial No. 598,000

4 Claims. (CL. 250—20)

This invention relates to new and useful improvements in a radio time switch and automatic tuner.

The invention has for an object the construction of a radio time switch which is characterized by the ability of being capable of turning "on" a radio set at a pre-determined time and thereafter of turning "off" the radio set on another pre-determined time.

10 Another object of this invention is the construction of a radio time switch which is capable of turning "off" a radio set at a pre-determined time and at the subsequent pre-determined time to turn "on" the radio set.

15 As a still further object this invention proposes the construction of a radio time switch which is capable of either turning "on" or only turning "off" the radio set.

The invention has for a still further object 20 the construction of a device which is characterized by the ability of being capable of turning the radio set "off" at a pre-determined time and simultaneously changing the station which is being received by the set to another pre-determined station and thereafter turning the radio set "on" at the newly set station at the pre-determined time.

The invention has for a still further object the construction of the radio time switch in a manner so that it is capable of operating according 25 to various variations and sequences hereinafter more fully described.

It is a still further object of this invention to construct a device of the class described which 30 is of simple durable construction, dependable in use and efficient in operation and which can be manufactured and sold at a reasonable cost.

For further comprehension of the invention, 35 and of the objects and advantages thereof, reference will be had to the following description and accompanying drawings, and to the appended claims in which the various novel features of the invention are more particularly set forth.

40 In the accompanying drawings forming a material part of this disclosure:—

Fig. 1 is a front elevational view of a time clock constructed according to this invention.

Fig. 2 is a rear elevational view of Fig. 1.

50 Fig. 3 is an inside view of the rear cover of the clock shown in Fig. 2.

Fig. 4 is a sectional view taken on the line 4—4 of Fig. 2.

55 Fig. 5 is a front elevational view of a portion of the inside of the clock seen as though look-

ing in the direction of the line 5—5 of Fig. 6.
Fig. 6 is a plan view of Fig. 5.

Fig. 7 is a fragmentary perspective view of a portion of a catch which holds the time controlled switch in an open position.

5 Fig. 8 is an enlarged fragmentary detailed view of a portion of Fig. 6.

Fig. 9 is a fragmentary enlarged detailed view of another portion of Fig. 6.

Fig. 10 is an elevational view of a switch which 10 controls the re-setting of the radio set, shown in greater detail in Fig. 13.

Fig. 11 is a front elevational view of a radio 15 panel equipped with the time switch shown in Fig. 1.

Fig. 12 is a fragmentary plan view of a portion of the radio set seen as though taken on the line 12—12 of Fig. 11.

Fig. 13 is a sectional view taken on the line 15—13 of Fig. 12.

20 Fig. 14 is a schematic wiring diagram of the device.

The radio time switch, according to this invention, comprises a clock 10, a pair of switches 11 and 12 associated with the clock and adapted 25 to be selectively closed and opened respectively at pre-determined time by the operation of the clock and hereinafter known respectively as an "on" switch and an "off" switch. A radio control circuit 13 includes a "radio on" switch 14. 30 An "off and on or only on" circuit 15 including said "on" switch 11 and "off" switch 12 is shunted across the radio circuit 13 and is connected with a double throw double pole single pole switch 16. An "on and off or only off" circuit 17 includes the 35 "off" switch 12 and the "on" switch 11 and is shunted across the radio circuit 13 and is connected with the switch 16. These circuits will be explained in further detail hereinafter.

The clock 10 may be any conventional type of 40 clock. As shown in the drawings, it comprises an electric clock having a frame 21 supporting the various parts thereof. More particularly, a motor 22 is connected with drive wheel 23 in mesh with the minute hand gear 24. A pinion gear 45 25 is coaxially fixed upon the minute gear 24 and meshes with an idler 26 carrying a pinion 27 in mesh with the hour gear 28. A conventional hour hand 29 is connected with the hour gear and a minute hand 30 with the minute gear 24. 50 The hands 29 and 30 work across the face of a clock dial 31. The clock may be set by a knob 32 which extends through the back of the clock and which is connected with a pinion 33 meshing with the idler 26. The clock also includes a coil 55 55

34 which is shunted across the supply of current to the radio circuit 13. The details of the operation of the clock will not be gone into since anyone familiar with the art will recognize and 5 understand the operation thereof.

The association of the clock 10 with the "on" and "off" switches 11 and 12 respectively, consists in the provision of a pinion 35 meshing with the hour gear 28 and in mesh with a pair of gears 10 36, 37. The gears 36 and 37 are loose upon setting stems 38 and 39 respectively. These stems are formed with heads on their rear ends and project from the rear of the clock. Each of the stems has a transverse pin 40 adapted to engage in recesses 41 in the hubs of the gears 36 15 and 37 respectively so as to allow the gears to move longitudinally relative to the pins 40. Spring catch arms 42 and 43 are respectively mounted upon a support element 44 attached upon the frame 21 of the clock and spring 43 20 is insulated from the support element 54. These spring members 42 and 43 are against the hubs of the gear 36 and the insulated hub 37 of gear 37 and normally tend to urge the gears against the pins 41. Each of the spring members 42 and 43 25 have their ends 45 turned at right angles and adapted to engage fingers 46 stamped from control levers 47 and 48 respectively for the operation of the "on" and "off" switches. The fingers 30 46 have one of their sides straight and the other curved so that the levers 47 and 48 may be moved outwards and during such motion the curved portions of the fingers 46 ride beneath the turned ends 45 and thereafter the flat sides of the fingers 35 act against the turned ends 45 and hold the levers 47 and 48 in the set position. Knobs 49 and 50 are attached respectively upon the ends of the levers 47 and 48 and extend through slots 51 in the front of the clock so that the levers 40 may be set from the exterior of the clock.

Springs 52 act between the levers 47 and 48 and the frame 21 to normally urge the levers together. The "off" switch 12 consists of the lever 48 and its action with the spring element 45 43. It is at these points that the circuit is broken when the lever 48 moves off from its contact with the spring element. The "on" switch 11 constitutes the lever 47 which carries the extension 60 and the connection between the extension 60 and the insulated stationary contact 61. It should be recognized that the stems 38 and 39 may be turned to pre-determined positions to control the closing of the switches 11 and 12. On each of the stems 38 and 39 there is a hand 55 63 which is located upon the front face of the clock and work across dials 64 and 63 which are respectively marked "on" and "off" to indicate the setting when the "on" or the "off" switch will close. When the gears 36 and 37, rotated by the clock mechanism, reach positions in which the recesses 41 engage the pins 40, then the springs 42 and 43 move the gears 36 and 37 longitudinally and the ends 45 release the levers 47 and 48 so that the springs 52 move the levers. 60 65 The radio circuit 13 includes a plug 66 which is adapted to be connected with a radio set to control the operation of the set. Such connection is generally known and will not be necessary to go into detail here. The radio circuit 13 includes the radio plug 66 which is connected with the lead 67 leading to the pole 68 of the double throw switch 16. The circuit then continues through the lead 69 to the pole 70 of the double throw switch. The switch 14 is interposed in 70 75 the lead 69. The circuit is concluded by the lead

71 from the pole 70. The purpose of switch 14 is to close the circuit of the radio set when the switch is thrown to the "To Radio Set" position, regardless of the setting of the time switch. When the switch is thrown in the "To Clock" position, the switch is open and the radio set is controlled by the setting of the time switch. 5

The re-setting switch 18 comprises a lever 78 which is pivotally mounted at its bottom end 79 and is urged in one direction by a spring 80. The top of this lever extends through a slot 81 in the panel board of the radio set and is there equipped with a knob 82 so that the lever may be moved from the outside. The lever 78 is provided with a projecting tongue 83 adapted to pass in one direction but be held from moving in the other direction against a spring member 84 which is mounted upon the back of the panel of the set. The lead 57 is connected with an insulated stationary contact 85 from which a flexible lead 86 20 extends to a contact finger 87 mounted upon the lever 78, and is insulated therefrom. In the caught position of the lever 78 the finger 87 engages with an insulated stationary contact 88 from which a lead 89 extends to the motor 19. 25 The motor 19 is connected with a gear system 90 terminating in a gear 91 upon the shaft 92 of the control dial 93 of the radio set. As this dial is turned the condensers 94 of the set accomplish tuning. The details of this arrangement 30 will not be shown since it forms no part of the invention.

A pinion 95 connects the gear 91 with another gear 96 free upon a shaft 97. The latter is held frictionally from rotation by a spring 97' when 35 the gear 96 turns. The shaft 97 extends through the panel of the set and carries a second disc 98 which may be read through an opening in the front of the panel. The hub of the gear 96 is provided with a recess 99 adapted to engage a 40 pin 100 upon the spindle 97. The spring arm 84 normally acts against the gear 96 to urge it against the pin 100 upon the spindle 97. A control for turning the disc 98 is provided and comprises a gear system 101 which terminates in a knob 102 45 upon a control stem 103. The arrangement allows the knob 102 to be turned for turning the shaft 97 and the dial 98 so that it may be set to a station subsequently. As the dial 98 turns the spindle 97 is correspondingly moved and the 50 location of the pin 100 is changed relative to a cutout 99 in the hub of the gear 96. If the pin 100 moves out from the cutout 99, the gear 96 is forced forwards and moves the spring arm 84 to engage the lever 78 so that the lever 78 is 55 held with the contacts 87 and 88 closed if manually moved against the action of spring 80.

The operation of the device may best be traced by first assuming the switch 16 to be thrown so as to connect the poles 70 and 74, and the poles 60 77 and 68, that is, so that the switch handle indicates the "off and on or on only position" shown in Fig. 2. The levers 47 and 48 must next be moved by the knobs 49 and 50 to set the "on" and "off" switches 11 and 12. Then the time 65 control may be set so that the hands 63 point to the hours when it is desired to have the radio set turned "off then on or on only". For example the current may be traced from the lead 71 to the pole 70, the pole 74, along lead 73, to the ground 70 59. Then the current continues to the grounded lever 48, the switch 12 across to the spring catch 43, the lead 53 to the pole 75 through shunt connection 20 to the pole 77 then across to the pole 68 along lead 67 through the radio plug 66. It is 75

readily seen that when the "off" time is reached the lever 48 will be released so that the "off" switch 12 operates and breaks the circuit through the radio set. Some time after, as pre-determined by the setting of the "on" switch, the lever 47 will be released so that the "on" switch 11 functions and the circuit then is closed from the ground 59 through the lever 47, the extension 60, contact 61, lead 62, pole 68, lead 67 and the radio plug 66. Thus the radio set now is functioning. If it were previously desired turn the radio set on at a certain time only the switch 12 should have been left off and only the switch 11 moved to its set position. Consequently, when the proper time arrives the lever 47 will be released for turning the radio set on.

When the switch 16 is thrown in the other direction, that is, to close the circuit between poles 70 and 75, in other words to operate the switch 16 in the direction of the notations "on" and "off" shown in Fig. 2, the time switch is now in condition to function to turn the set on and off or only off. For example, the current may be traced from lead 71 across to the pole 75, lead 73, spring contact 43, the switch 12, the ground, the lever 47, the switch 11, the extension 60, the contact 61, the lead 62, the pole 68, the lead 67 and the radio plug 66. Consequently, when the "on" switch operates this circuit will be closed and the radio set will be on. Thereafter, when the "off" switch 12 operates the circuit will be broken at the "off" switch and the radio set will cease to function. If so desired, only the "off" switch 12 could have been set to its operating position so that the radio set is on continuously and turned off at a pre-determined time when the "off" switch 12 breaks the circuit.

There is another setting, namely, to cause the time switch to turn the radio set off at a pre-determined time, reset the radio to a new pre-determined station and at another pre-determined time to turn it on so that the new station functions. To do this the switch 18 is closed and the dial 98 set to the new station. Consequently, should the motor 19 operate and turn the radio control 93 until the new station is reached, the rotation will be transmitted to the gear 96 and the pin 100 will allow the spring 84 to move the gear at the new setting and thus break the circuit at the switch 18. Now then, the current may be traced starting at the lead 71 to the pole 70, the pole 74, the lead 73, the ground 59, the grounded lever 48, the switch 12, the contact spring 43, lead 53, pole 75, lead 20, pole 77, pole 68, lead 67 and radio plug 66. At the pre-determined time the "off" switch 12 breaks the circuit to turn the radio set off. As the "off" switch 12 breaks the circuit a new circuit is closed through the extension 55 and the stationary contact 56. A current then may flow which may be traced from the ground 59 to the lever 48, the extension 55, the contact 56, lead 57, contact 85, lead 86, extension 87, contact 88, lead 89, the motor 19, and lead 76 which concludes the circuit. The motor 19 then functions and causes turning of the gears 91 and 96. As the gear 91 turns the station of the set is being changed and when the new desired station is reached the gear 96 will move as allowed by the recess 99 and the pin 100 so that the spring arm 84 releases the lever 78 and the switch 18 then automatically moves to its open position. This breaks the circuit through the electric motor which ceases operation and the set now is in the new position. Sometime after, when the clock turns on the "on"

switch the circuit is then closed through the radio set and may be traced from the ground 59 to the lever 47 through the "on" switch 12, the extension 60, the contact 61, lead 62, pole 68, lead 67, and the radio plug 66.

While we have shown and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:—

1. A radio time switch comprising a body, a pair of shafts turnably mounted on said body and provided with radial pins, a gear free on each shaft and having hubs with recesses for said pins and meshing with a clock driven gear, spring arms urging said gears against said pins and having ends moved forward when said shafts are turned to force said pins out from said recesses, pair of movable levers mounted on said body and urged into neutral positions and manually movable to positions engaged on said ends in the forward positions of said ends, a switch comprising one of said levers and its contractable spring arm and hereafter called an "off" switch, a switch comprising engaging contacts on said body and on said other lever in its neutral position and hereinafter called an "on" switch, a power circuit of a radio receiver, a double pole double throw switch, a circuit connecting said "off" switch in series with said power circuit in one position of said double pole double throw switch, a circuit connecting said "on" switch in series with said power circuit in the other position of said double throw switch, another switch comprising engaging contacts on said body and said lever of the "off" switch in its neutral position and hereinafter called a "master" switch, tuning mechanism operated with a motor, a turnable shaft provided with a radial pin, a gear free on said shaft and having a hub with a recess for said pin and meshing with a pinion driven by said tuning mechanism, a spring arm urging said gear against said pin and having an end moved forward when said shaft is turned to force said pin out from said recess, a movable lever urged into a neutral position and manually movable to a position engaging on said end in the forward position of said end, a switch comprising engaging contacts on said lever and a stationary element in the moved position of said lever and hereinafter called a "resetting" switch, and a circuit shunted across said "off" switch circuits and the said power circuit and including in series said "master" switch, the "resetting" switch and said motor.

2. A radio time switch comprising a body, a pair of shafts turnably mounted on said body and provided with radial pins, a gear free on each shaft and having hubs with recesses for said pins and meshing with a clock driven gear, spring arms urging said gears against said pins and having ends moved forward when said shafts are turned to force said pins out from said recesses, pair of movable levers mounted on said body and urged into neutral positions and manually movable to positions engaged on said ends in the forward positions of said ends, a switch comprising one of said levers and its

contractable spring arm and hereinafter called an "off" switch, a switch comprising engaging contacts on said body and on said other lever in its neutral position and hereinafter called an "on" switch, a power circuit of a radio receiver, a double pole double throw switch, a circuit connecting said "off" switch in series with said power circuit in one position of said double pole double throw switch, a circuit connecting said "on" switch in series with said power circuit in the other position of said double throw switch, another switch comprising engaging contacts on said body and said lever of the "off" switch in its neutral position and hereinafter called a "master" switch, tuning mechanism operated with a motor, a turnable shaft provided with a radial pin, a gear free on said shaft and having a hub with a recess for said pin and meshing with a pinion driven by said tuning mechanism, a spring arm urging said gear against said pin and having an end moved forward when said shaft is turned to force said pin out from said recess, a movable lever urged into a neutral position and manually movable to a position engaging on said end in the forward position of said end, a switch comprising engaging contacts on said lever and a stationary element in the moved position of said lever and hereinafter called a "resetting" switch, and a circuit shunted across said "off" switch circuits and the said power circuit and including in series said "master" switch, the "resetting" switch and said motor, springs being connected with all of said levers for urging them into the neutral positions. 5

4. A radio time switch comprising a body, a pair of shafts turnably mounted on said body and provided with radial pins, a gear free on each shaft and having hubs with recesses for said pins and meshing with a clock driven gear, spring arms urging said gears against said pins and having ends moved forwards when said shafts are turned to force said pins out from said recesses, a pair of movable levers mounted on said body and urged into neutral positions and manually movable to positions engaged on said ends in the forward positions of said ends, a switch comprising one of said levers and its contractable spring arm and hereinafter called an "off" switch, 10 a switch comprising engaging contacts on said body and on said other lever in its neutral position and hereinafter called an "on" switch, a power circuit of a radio receiver, a double pole double throw switch, a circuit connecting said "off" switch in series with said power circuit in one position of said double pole double throw switch, a circuit connecting said "on" switch in series with said power circuit in the other position of said double throw switch, another switch comprising engaging contacts on said body and said lever of the "off" switch in its neutral position and hereinafter called a "master" switch, tuning mechanism operated with a motor, a turnable shaft provided with a radial pin, a gear free on said shaft and having a hub with a recess for said pin and meshing with a pinion driven by said tuning mechanism, a spring arm urging said gear against said pin and having an end moved forward when said shaft is turned to force said pin out from said recess, a movable lever urged into a neutral position and manually movable to a position engaging on said end in the forward position of said end, a switch comprising engaging contacts on said lever and a stationary element in the moved position of said lever and hereinafter called a "resetting" switch, and a circuit shunted across said "off" switch circuits and the said power circuit and including in series said "master" switch, the "resetting" switch and said motor, 15 20 25 30 35 40 45 50 55 60 65 70 75 80 85 90 95 100 105 110 115 120
